UNITED STATES PATENT OFFICE.

THADDEUS S. GRIMES, OF COLUMBUS, GEORGIA, ASSIGNOR TO LUMMUS COTTON GIN COMPANY, OF COLUMBUS, GEORGIA, A CORPORATION OF GEORGIA.

GINNING-RIB.

1,300,162.

Specification of Letters Patent.

Patented Apr. 8, 1919.

Original application filed December 2, 1916, Serial No. 134,714. Divided and this application filed June 15, 1917. Serial No. 175,008.

To all whom it may concern:

Be it known that I, THADDEUS S. GRIMES, of Columbus, in the county of Muscogee and State of Georgia, have invented certain new and useful Improvements in Ginning-Ribs; and I do hereby declare the following to be a full, clear, and exact description of the invention, such as will enable others skilled in the art to which it appertains to make and use the same.

I have found in ginning that lint will accumulate from the under side of the ribs and gather between and around the ribs at the ends of the ginning spaces, that is, where the ribs are attached to the rib rail. This causes a choking in the ginning spaces between the ribs and retards the effective action of the saws. My object is to overcome this difficulty.

Figure 1 shows the general design of the rib and Figs. 2 and 3 are detail perspectives showing its attachment to the rail.

The rib 1 is shown secured at its lower end to a rail 2, its upper end being supported by a rail 3 which will be understood to be intended for use adjacent a ginning roll box. The arrangement and operation of the ribs may be as shown and described in Letters Patent No. 1,244,196, issued on my application October 23, 1917, of which this case is a division.

The rail 3 is formed with a strip 4 at its edge adjacent the saw cylinder, that is, at the point of engagement of the ribs. Each rib is formed with a lug 5 to bear against the front face of the rail and is rabbeted to receive the strip 4. The extremities 6 of the ribs are rigidly secured to the rail.

The ribs have recesses 7 extending toward their ends 6 from points just over strip 4, the oppositely disposed recesses coacting to form widened slots at the meeting edges of adjacent ribs. At their points of contact

with the inner edge 8 of the strip, however, and rearward therefrom, the ribs are in close contact.

It will be understood that the main portions of the ribs are sufficiently spaced to permit the gin saws to rotate through them. It will be noted that the strip 4 is in advance of the point 9 at which the ribs closely contact with each other. This renders it impossible for the lint to be pulled through the joint between the ribs. It is prevented from doing so by the strip. The slots formed by the recessed portions of contiguous ribs constitute channels permitting of the ready release of the cotton partially pulled through by the saws and enables this cotton to get back into the roll box.

I claim as my invention:

1. The combination with a pair of ginning ribs, of a rail to which said ribs are secured, said rail having a strip at its forward edge, said ribs extending over being spaced apart in advance of, said strip and being closely united at the rear of said strip.

2. The combination with a pair of ginning ribs, of a rail to which said ribs are secured, said rail having a strip at its forward edge, said ribs having recesses formed in their adjacent surfaces at a point above said strip and extending rearward thereof.

3. The combination with a pair of ginning ribs, of a rail to which said ribs are secured, said rail having a strip at its forward edge, said ribs having lugs bearing against the front of said rail and being cut away to receive said strip, the adjacent faces of said ribs being spaced apart over and in front of said strip and having shoulders at the rear edge of said strip in close contact with the latter and with each other.

In testimony whereof I have signed this specification.

THADDEUS S. GRIMES.

Copies of this patent may be obtained for five cents each, by addressing the "Commissioner of Patents, Washington, D. C."

It is hereby certified that in Letters Patent No. 1,300,162, granted April 8, 1919, upon the application of Thaddeus S. Grimes, of Columbus, Georgia, for an improvement in "Ginning-Ribs," an error appears in the printed specification requiring correction as follows: Line 65, claim 1, after the word "over" insert a comma and the word *and*; and that the said Letters Patent should be read with this correction therein that the same may conform to the record of the case in the Patent Office.

Signed and sealed this 29th day of April, A. D., 1919.

[SEAL.]

R. F. WHITEHEAD,

Acting Commissioner of Patents.

Cl. 13—13.
